MANIFOLDING STATIONERY

Harry J. Waechter, Mount Healthy, Ohio, assignor to Paul Benninghofen and Fritz G. Diesbach, Hamilton, Ohio, trustees

Original application February 20, 1941, Serial No. 379,849. Divided and this application December 30, 1942, Serial No. 470,600

3 Claims. (Cl. 282—21)

This invention relates to manifolding or continuous forming stationery of the type utilized in autographic registers which present the forms successively upon a writing platen and which are effective for feeding, aligning and delivering the forms.

More particularly, this invention is directed to improvements in manifolding stationery which comprises a plurality of superimposed forms; or in other words, a manifolding pack with the sets of forms separated from each other by means of weakened transverse lines which permit separation.

The present application constitutes a division of co-pending application Serial No. 379,849, filed February 20, 1941, and entitled "Autographic register," which application has now issued into Patent No. 2,326,108, dated August 10, 1943. The register disclosed in the co-pending application is effective for feeding the continuous form stationery of this invention.

It has been an object of the present inventor to provide manifolding stationery which is formed so as to permit accurate and positive alignment of the forms during each feeding operation and which may be fed through the same register for this purpose regardless of variation in the lengths of the forms. The improvements particularly lie in the arrangement of the feeding apertures so as to permit feeding, aligning and dispensing in a register of the type disclosed in the co-pending application.

In the co-pending application, the inventor has provided an autographic register which utilizes cooperating sets of discs or rolls, upper and lower, to feed and align the improved forms by virtue of their feeding relationship to apertures in the forms. The rolls are manually operated by a crank which is fixed to one end of the shaft carrying the lower set of rolls. The upper rolls are in positive transmission connection with the lower rolls by gears, and are carried on a common shaft which is spring-urged to provide a peripheral contact between the two sets.

The feeding mechanism incorporates three sets of rolls. Two of these engage the forms marginally. The lower rolls of these sets are provided with cutaway or strip releasing spaces for freeing the strips from their contacting pressure at a given point in their revolution. At this point, a third set of rolls, engaging the strips medially, continues the feed until the forms, irrespective of their lengths, within practical limits, are advanced to a point a predetermined distance from the dispensing end. From this latter point, the

forms are advanced slightly by engagement of a second tread section on the two marginal rolls. Beyond this tread section, all three of the rolls are provided with cut-out sections which free the forms from all feeding pressure so that pins carried on the marginal rolls may engage corresponding apertures in the forms to align the forms and complete the feeding operation.

The improved stationery comprises a plurality of continuous strips of forms defined by weakened tear-off lines. Each form includes three apertures for cooperation with the three sets of rolls. An aperture disposed in the tear-off line medially of the strip is provided to cooperate with the middle feed rolls. The other two apertures are spaced laterally, one near each side of the form on a line parallel to, and slightly back from, the tear-off line to cooperate with the aligning pins which are carried on the lower marginal feed rolls. The side apertures may be spaced any desired distance from the side edges; that is, they need not be as near the sides as shown.

The superimposed strips are fed through the rolls in three stages; one, a major feeding operation, in which all three sets of rolls advance the strips; two, an adjusting feeding operation in which the compensating rolls are employed to feed the strips; and three, a minor feeding operation wherein the strips are absolutely aligned and the forms dispensed.

In the first stage, the strips are always advanced a distance slightly less than the shortest form to be used. In this stage all three of the lower feed rolls engage the strips.

In the second stage, cutaway or strip releasing sections in the peripheries of the two marginal feed rolls free the forms so that only the compensating feed roll is effective. The compensating feed rolls advance the forms until the middle apertures in the superimposed forms are all aligned between the two compensating rolls. At this point, the feeding contact of the compensating rolls is broken since the rolls contact each other through the apertures. Thus, it may be seen that within practical limits, any length of form may be employed. In the third stage, first, the forms are engaged by a short tread section on the marginal feed rolls and advanced slightly. Secondly, the forms are freed from the contacting pressure of all three sets of rolls by the cut-out sections in the peripheries of all three rolls and the pins carried by the marginal rolls engage in them to align the forms and dispense them.

Other objects and certain advantages of the present invention will be more fully apparent

from a description of the accompanying drawings, in which:

Figure 1 is a perspective view of the manifolding pack of this invention showing the forms folded on their lines of separation and arranged in zigzag form.

Figure 2 is a top plan view of one of the forms showing the relative positions of the apertures.

Figure 3 is a perspective view of the feeding rolls showing a pack of manifolding forms in 10 aligned position between the rolls.

Figure 4 is a sectional view of the compensating rolls taken on line 4—4, Figure 3, illustrating them just after the start of a feeding operation.

Figure 5 is a sectional view of one of the feed rolls taken on line 5—5, Figure 3, illustrating the feed rolls in the same relative position as the compensating rolls shown in Figure 4.

Figure 6 is a sectional view taken similar to Figure 4 in which the lower compensating roll 20 has been rotated through the feeding part of its rotation and is now in the idling or adjusting part of its rotation.

Figure 7 is a sectional view taken similar to Figure 5, showing one of the feed rolls in the same 25 relative position as the compensating rolls in Figure 6 and wherein the feed rolls are not in contact with the forms and therefore are ineffective.

Figure 8 is a sectional view taken similar to 30 Figures 4 and 6, showing the lower compensating roll at the completion of a rotation.

Figure 9 is a sectional view taken similar to Figures 5 and 7, showing one of the feed rolls in the same relative position as the compensating 35 rolls in Figure 8 and about to complete the feeding and alignment of the paper forms.

In order to make it more convenient to read the drawings and specifications in the respective applications, that is, the co-pending application and the present application, the parts are correspondingly numbered.

The strips of forms utilized here consist of lengths of paper having forms 11 defined by weakened cross lines 12. An aperture 13 is provided centrally for each form midway on a scored or perforated line 12, for cooperation with the compensating rolls. Just back of the line 12 in each case are apertures 14, one at each side of the strip for cooperation with the feed rolls.

The lower rolls are substantially larger than the upper rolls and include a pair of feeding rolls 34—34 and an adjusting or compensating feed roll 35. The shafts upon which the upper and lower rolls are carried are in positive transmission connection through meshing pinions (not shown). The feeding or translating rolls are operated by means of a crank handle 23 pinned to one end of a shaft 24 which carries the lower rolls. Each roll 34 carries a pin 38 extending radially slightly beyond the line of the periphery of the roll. The pins may be made integrally with the feed rolls, as shown, and are positioned on the inside of the roll in each case. The compensating feed roll 35 is mounted on the shaft 24 medially, between the two feed rolls.

The lower roll 35 has a single short cutaway or pressure relieving section 39 in its periphery. This portion 39 comes into effect only at the very end of the rotation. The lower feed rolls 34 each have two cutaway sections. One, indicated at 40 in each instance, corresponds to the cutaway section 39 in the lower compensating roll. These pressure relieving sections 39 and 40 come 75

into effect to free the forms so that the pins 38—38 carried with the feed rolls can make the final advance of the forms. The second cutaway section on the lower feed rolls, indicated at 41 in each instance, extends over slightly less than half of the periphery of the lower feed rolls. These cutaway sections 41—41 are provided to release the feeding pressure on the forms so that the compensating rolls can bring the forms into registry. A short tread section 42 is provided between the two cutaway sections on each lower feed roll to start the final feed operation just before the pins 38—38 come into operation.

Operation

In Figures 4 and 5, the compensating rolls 27, 35 and one set of the feed rolls 26, 34 respectively are shown near the start of a rotation. It will be noted that both are effective for advancing the forms. When the forms are advanced to a point where the middle aperture 13, which is ahead of the marginal apertures 14, comes between the compensating rolls, the start of the cutaway sections 41—41 on the feed rolls is adjacent the upper rolls. Therefore, the pressure of the feed rolls is released from the forms and only the compensating roll is effective. When all of the middle apertures in the superimposed forms are in registry, the upper and lower compensating rolls will contact each other through the apertures 13, and, as shown in Figure 6 of the drawings, the forms will be out of feeding contact with the rolls. This compensating roll also serves as a pre-aligner in that if one or more of the forms is lagging, the first form to reach the compensating rolls will stop when its middle aperture advances out of feeding contact with the compensating rolls and the rolls will, therefore, contact the lagging forms and advance them until all of the apertures register and the compensating rolls contact each other through them.

The rotation of the rolls after the compensating interval continues without feeding the forms until the tread sections 42—42 on the lower feed rolls come around to contact the forms. This stage is shown in Figure 9 of the drawings. The short tread sections 42—42 advance the forms slightly to bring the marginal apertures 14—14 forward to a position wherein the pins 38—38 enter them. As soon as the forms reach the point wherein the pins are established in the marginal apertures, the cut-out sections 39 and 40—40 in the peripheries of all three lower rolls come into effect to release all pressure on the forms. Therefore, the final advance is made by the pins to bring the forms into absolute registry.

Having described my invention, I claim:

1. A pack of sales forms of the type adapted to be fed through a manifolding machine, comprising superimposed strips of paper, including successively arranged sales forms separated by weakened transverse tear lines, said superimposed strips folded in zigzag form on said weakened tear lines, the strips making up the forms including for each form a series of three feed control apertures, two of said apertures disposed in transverse alignment adjacent the respective edges of the strips and the third aperture disposed forwardly of the last-named two and located on the weakened tear line, the corresponding apertures of the respective strips and forms being in alignment when the forms are zigzag folded.

2. A continuous strip of sales forms, said forms adapted to be separated along weakened trans-

verse tear lines, each form including three feed control apertures, one aperture located centrally and adjacent the tear line and the other two located in transverse alignment adjacent the respective sides of the strip and spaced from the first-named aperture longitudinally of the strip.

3. A pack of sales forms of the type adapted to be fed through a manifolding machine, comprising superimposed strips of paper, including successively arranged sales forms separated by weakened tear lines, said superimposed strips

folded in zigzag form on said weakened tear lines, the strips making up the forms including for each form a feed control aperture adjacent each respective longitudinal edge of the strips, said last-named apertures being in transverse alignment, and a third aperture disposed forwardly and medially of the last-named apertures, the corresponding apertures of the respective superimposed forms being in alignment when the forms 10 are zigzag folded.

HARRY J. WAECHTER.
